UNITED STATES PATENT OFFICE.

JULIEN A. GEHRUNG, OF ST. LOUIS, MISSOURI.

ELECTRICAL SIGNALING SYSTEM.

SPECIFICATION forming part of Letters Patent No. 680,036, dated August 6, 1901.

Application filed March 14, 1901. Serial No. 51,055. (No model.)

To all whom it may concern:

Be it known that I, JULIEN A. GEHRUNG, a citizen of the United States of America, and a resident of St. Louis, in the State of Missouri, have invented certain new and useful Improvements in Electrical Signaling Systems, of which the following is a specification.

The present invention relates to that system of signal transmission in which the sending and receiving stations are electrically connected together by a single line wire or conductor and with which the depression of any particular key of the sending instrument will cause an operation of the corresponding key of the receiving instrument.

The object of the present invention is in the main to provide a novel combination and construction of the component parts of the described type of signaling systems and which affords great simplicity and durability of parts, combined with great certainty and efficiency of operation, as will hereinafter more fully appear and be more particularly pointed out in the claims. I attain such object by the construction and arrangement of parts illustrated in the accompanying drawings, in which—

Figure 1 is a diagrammatic view of the present improved system arranged and adapted for use as a printing - telegraph apparatus; Fig. 2, a vertical sectional elevation of the combined sending and receiving instrument for use in the separated stations between which messages are intended to be sent and printed as received; Fig. 3, an enlarged fragmentary elevation of the series of coacting circuit-closing mechanisms of the series of selective electromagnets of the present invention; Fig. 4, an end elevation of the same, illustrating the operating electromagnet and connections for an individual circuit-closing mechanism; Fig. 5, an enlarged detail sectional elevation illustrating the means whereby the different portions or parts of the circuit-closing mechanism are insulated from each other.

Similar numerals of reference indicate like parts in the several views.

In the accompanying drawings the present invention is illustrated or embodied in the form of a printing-telegraph apparatus in

which the sending and receiving stations are each provided with a counterpart combined message sending and receiving apparatus connected together by a single main-line wire or conductor, the sending mechanism whereof will comprise as follows:

1 represents a series of sending-keys, corresponding in number to the different characters, letters, &c., intended to be transmitted and each provided with its individual circuit-closing contacts 2, each of which is in turn adapted to close in an individual manner the circuit of the main-line battery 3 through the individual branch wires 4 and the electrical resistance 5 with the main-line wire or conductor 6, which connects the sending and receiving stations together.

The electrical resistance 5, above mentioned, will usually comprise a single elongated coil of resistance - wire, to which the series of branch wires or conductors 4 are connected at regular intervals in order to subdivide the same into a continuous series of resistance-sections, so that the operation of any one sending-key will introduce a degree of resistance into the main-line circuit different from that introduced into said circuit by any of the other sending - keys. For example, with a depression of the lowermost key 1, in diagram view Fig. 1 no resistance will be introduced into the main-line circuit, and in consequence the entire electromotive force of the main-line battery 3 will be introduced into such circuit, while with a depression of each successive sending-key toward the upper end of the diagram a graded and progressively - increased amount of resistance will be introduced in the main-line circuit, with a corresponding decrease in the electromotive force of the current.

The receiving mechanism of the aforesaid combined sending and receiving machine will comprise as follows: 7 represents a series of selective electromagnets corresponding in number with the before-mentioned series of sections in the electrical resistance 5 and with the series of sending-keys 1, the windings of which are arranged in parallel and connected at one end with the main-line wire or conductor 6 and at the other end with a return wire or conductor 8, which may run to ground or to an opposite pole of the main-

line battery 3, where an all-metallic circuit is employed in the system. The described series of selective electromagnets 7 have in the present invention varied intensities or 5 electromotive forces graded in a progressive manner to correspond with the graded strengths of the motive current furnished thereto by the sending-keys 1, as heretofore described. In the arrangement illustrated 10 in diagram view Fig. 1 the lowermost sending-key transmits the entire electromotive force of the battery to the main line, and each succeeding sending-key transmits a proportionately less amount of electromotive 15 force to such main line, as heretofore mentioned, and accordingly the same order or arrangement of the series of selective electromagnets 7 should prevail—to wit, the uppermost of said magnets or the one at the point 20 at which the current enters the message-receiving mechanism will have the lowest electromotive force, and the electromotive force of each succeeding electromagnet of the series will have a proportionately-increased 25 strength.

9 represents the armatures of the respective selective electromagnets 7. Each armature is provided with a yoke-shaped piece carrying in an insulated condition the contact 30 posts or fingers 10 and 11 of a circuit-closer, which is individual to its selective electromagnet 7 and adapted to close the circuit of a local battery 12 upon the individual message-recording device, which in 35 the construction shown in the drawings as illustrative of the present invention is an individual actuating electromagnet 13 of a type-bar 14 of a telegraphic-printing instrument similar in construction and operation 40 to an ordinary electrically-actuated type-writing machine common to the class of printing-telegraphs to which the present invention relates. This part of the present invention in its scope embraces the operation 45 of any other recording means used in electric signaling in lieu of a series of type-bars—as for instance, the annunciator-drop of a hotel-annunciator or other like electric signaling apparatus.

50 With the present invention employed in a printing-telegraph system, as illustrated in Figs. 1 and 2 of the drawings, the message-sending mechanism is provided with a separate sending-key, local-battery-circuit closer, 55 and intermediate accessories for each type-bar to be actuated in the message-receiving mechanism, a separate set thereof for the word-spacing mechanism, another for the carriage-return mechanism by which the paper-carriage is returned after a line has been 60 printed, and one or more separate sets thereof for the platen-shifting mechanism, when a type-writing mechanism having such provision is employed in connection with the present system, such platen-shift being adapted 65 to effect a change in the printing operation from capitals to lower case, and vice versa.

Such different automatic mechanisms are well known in the art of electrical type-writers and printing-telegraphs and no extended description of the same will be given herein, as their details of construction constitute no part of the novel subject-matter of the present invention. 70

The circuit-closers for the local-battery 75 circuits, heretofore referred to, may be of any usual construction, the only requisite for the purpose of the present invention being that one of the contact-fingers 11 upon the armature of one of the electromagnets 7 will be 80 adapted under certain conditions to contact with the next adjacent contact post or finger 10, carried by the armature of the next adjacent electromagnet 7 to close the local-battery circuit to operate the actuating-electromagnet 13 of its particular type-bar 14 or other character-recording device, and under certain other conditions to prevent such closure of the said local circuit and a consequent 85 operation of said type-bar 14 or other character-recording device. 90

In the present invention the first-mentioned condition will occur when the electric current passing along the main line or conductor 6 lacks sufficient strength or electromotive 95 force to energize the second or last mentioned selective electromagnet 7 to cause the same to attract its armature; but possesses sufficient strength or electromotive force to energize the first or initially mentioned selective 100 electromagnet to cause the same to attract its armature, while the other or reverse condition above mentioned will occur when the electric current passing along the main line or conductor 6 has sufficient strength or electromotive force to energize the last-mentioned selective 105 electromagnet to attract its armature and draw the contact-point 10, carried by such armature, out of the path of the contact-finger 11, carried by the first or initially 110 mentioned selective electromagnet. 115

It is evident from the foregoing description that the amount of electrical resistance included in the main-line circuit and the consequent electromotive force of the same varies with the particular sending-key of the series that is actuated or depressed and that with a corresponding construction of the selective electromagnets in the message-receiving mechanism, as heretofore described, it follows that on the depression of any particular sending-key a current will be sent along the main line having the requisite amount of electromotive force to actuate its particular selective electromagnet, as well as those of 125 weaker resistance, and close its particular local-battery circuit upon the operating-electromagnet of its particular type-bar or other equivalent device, but insufficient to actuate any of the subsequent selective electromagnets, the windings of which require a higher electromotive force to actively operate the same. 130

Assuming that an intermediate sending-

key of the system illustrated in Fig. 1 be depressed to energize its particular selective electromagnet, all the selective electromagnets below such particular selective electromagnet will remain dormant owing to the comparatively-reduced electromotive force existing in the main-line circuit, while all the selective electromagnets above such particular selective electromagnet will be energized by the comparatively high electromotive force existing in the main-line circuit, and all of such last-mentioned selective electromagnets would actively operate their armatures to close their individual local-battery circuits of the operating-electromagnets of their particular type-bars were it not for the particular arrangement heretofore described of the interdepending circuit-closers, and accordingly with such interdepending of circuit-closers the first-mentioned or predetermined selective electromagnet will by the movement of its armature bring its contact-finger 11 into electrical contact with the contact post or finger 10, carried by the armature of the next lowermost selective electromagnet, to close the particular local-battery circuit and operate the particular type-bar. Such last-mentioned contact post or finger 10 retains its position to enable the companion contact-finger 11 to have electrical contact therewith owing to the fact that the electromotive force in the main-line circuit is not sufficiently high to energize the windings of the next lowermost selective electromagnet, so as to cause the same to attract its armature upon which said contact-finger 10 is carried, while in the case of the series of selective electromagnets above the first-mentioned or predetermined one the armatures will all be attracted to remove the series of contact-points 10 carried thereby out of the path of the series of companion contact-points 11 to prevent electrical contacts between the same, and thus prevent the establishment of any local-battery circuit other than the particular one intended to operate the particular type-bar of the particular sending-key that is operated.

In the present improvement the lowermost selective electromagnet of the series will have its contact point or finger corresponding to the contact-point 10 of the remainder of the series in the form of a finger or contact-post 10', fixed on the main frame of the apparatus, as illustrated in Figs. 1 and 3.

With a release of a particular sending-key the main-line circuit will be broken, and the various parts will automatically return to their normal position ready for a subsequent action.

The actuating-electromagnets 13 of the type-bars 14 are adapted to actuate the letter-spacing mechanism 15 of the printing mechanism in substantially the same manner as is now effected in the ordinary type-writing machine, and no other provision will be required to effect such spacing between letters. The spacing between words will, however,

require a separate provision, and in the present construction such provision is supplied by a separate sending-key, selective electromagnet, interdepending circuit-closer, and operating-electromagnet in the local-battery circuit, the armature of which has operative connection with the spacing-escapement of the type-writing mechanism. In like manner a counterpart arrangement of such parts will be provided in connection with any usual electrical line-shift mechanism, with any automatic carriage-return mechanism, as well as with a platen-shift mechanism, where one is employed. No novelty is, however, claimed herein for such automatic provisions, as the same are usual and common in the systems of printing-telegraphs heretofore proposed.

In the particular type of the interdepending circuit-closing contact points or fingers for the series of selective electromagnets illustrated in Figs. 1, 3, 4, and 5 of the drawings, 10 represents contact posts or fingers fixed in an insulated manner to one arm or fork of the upper portion of a vertically-moving yoke-frame 16 and connected to one pole of the local battery 12, operating the type-bars or other recording or indicating mechanisms. 11 represents movable companion contact-fingers connected by their individual wires or conductors to the other pole of the local battery 12 and normally out of contact with the contact-fingers 10. 17 represents fixed brackets, to which the movable contact-fingers 11 are fulcrumed at one end. The central portions of said contact-fingers have operative pivotal connection to an arm or fork of the next adjacent vertically-moving yoke-frame 16, in manner clearly indicated in Fig. 3, so as to have movement therewith. 18 is a screw coupling-piece of hard rubber or other like insulating material for connecting the sections or parts of the yoke 16 together in an insulated manner. 19 is a bell-crank lever carrying the armature of a selective electromagnet 7 and having operative link connection 20 with the vertically-moving yoke-frame 16, so as to impart vertical movement to the same. 21 is a spring tending to draw the armature away from the electromagnet 7, and 22 is a secondary spring tending to force the yoke-frame 16 upward into its normally-raised condition.

Having thus fully described my said invention, what I claim as new, and desire to secure by Letters Patent, is—

1. In an electrical signaling system, the combination of a main line, a main-line battery, an electrical resistance divided into sections that are connected in series, individual branch wires between the main-line battery and the resistance-sections, a series of sending-keys controlling the branch circuits and adapted to send to the main line signals of a graded electromotive force, a series of selective electromagnets having windings of a graded electromotive force, a series of interdepending circuit-closers actuated by said se-

lective magnets, a series of operating-electromagnets controlled by said circuit-closers, and a series of recording devices actuated by said operating-electromagnets and adapted to record signals at a distant station, substantially as set forth.

2. In an electrical signaling system, the combination of a main line, a main-line battery, an electrical resistance divided into sections that are connected in series, individual branch wires between the main-line battery and the resistance-sections, a series of sending-keys controlling the branch circuits and adapted to send to the main line signals of a graded electromotive force, a series of selective electromagnets the windings of which are arranged in parallel and have a graded electromotive force, a series of interdepending circuit-closers actuated by said selective electromagnets, a series of operating-electromagnets controlled by said circuit-closers and a series of recording devices actuated by the operating-electromagnets and adapted to record signals at a distant station, substantially as set forth.

3. In an electrical signaling system, the combination of a main line, a main-line battery, an electrical resistance divided into sections that are connected in series, individual branch wires between the main-line battery and the resistance-sections, a series of sending-keys controlling the branch circuits and adapted to send to the main line signals of a graded electromotive force, a series of selective electromagnets the windings of which are arranged in parallel and have a graded electromotive force, a series of interdepending circuit-closers actuated by said selective electromagnets, one contact-finger of each local-circuit closer being controlled by one selective electromagnet and the companion contact-finger by the next adjacent selective electromagnet, a series of operating-electromagnets controlled by said circuit-closers, and a series of recording devices actuated by the operating-electromagnets and adapted to record signals at a distant station, substantially as set forth.

4. In an electrical signaling system, the combination of a main line, a main-line battery, an electrical resistance divided into sections that are connected in series, individual branch wires between the main-line battery and the resistance-sections, a series of sending-keys controlling the branch circuits and adapted to send to the main line signals of a graded electromotive force, a series of selective electromagnets the windings of which are arranged in parallel and have a graded electromotive force, a series of interdepending circuit-closers actuated by said selective electromagnets, one contact-finger of each local-circuit closer being controlled by one selective electromagnet and the companion contact-finger by the next adjacent selective electromagnet and the final contact-finger of the series by a fixed support on the main frame, the said companion finger comprising a bar or member fulcrumed at one end to a stationary bracket and pivotally connected at its center with an extension on the armature of a selective electromagnet, a series of operating-electromagnets controlled by said circuit-closers, and a series of recording devices actuated by the operating-electromagnets and adapted to record signals at a distant station, substantially as set forth.

frame, a series of operating electromagnets controlled by said circuit-closers, and a series of recording devices actuated by the operating-electromagnets and adapted to record signals at a distant station, substantially as set forth.

5. In an electrical signaling system, the combination of a main line, a main-line battery, an electrical resistance divided into sections that are connected in series, individual branch wires between the main-line battery and the resistance-sections, a series of sending-keys controlling the branch circuits and adapted to send to the main line signals of a graded electromotive force, a series of selective electromagnets the windings of which are arranged in parallel and have a graded electromotive force, a series of interdepending circuit-closers actuated by said selective electromagnets, one contact-finger of each local-circuit closer being controlled by one selective electromagnet and the companion contact-finger by the next adjacent selective electromagnet, the said companion finger comprising a bar or member fulcrumed at one end to a stationary bracket and pivotally connected at its center with an extension on the armature of a selective electromagnet, a series of operating-electromagnets controlled by said circuit-closers, and a series of recording devices actuated by the operating-electromagnets and adapted to record signals at a distant station, substantially as set forth.

6. In an electrical signaling system, the combination of a main line, a main-line battery, an electrical resistance divided into sections that are connected in series, individual branch wires between the main-line battery and the resistance-sections, a series of sending-keys controlling the branch circuits and adapted to send to the main line signals of a graded electromotive force, a series of selective electromagnets the windings of which are arranged in parallel and have a graded electromotive force, a series of interdepending circuit-closers actuated by said selective electromagnets, one contact-finger of each local-circuit closer being controlled by one selective electromagnet and the companion contact-finger by the next adjacent selective electromagnet, and the final contact-finger of the series by a fixed support on the main frame, the said companion finger comprising a bar or member fulcrumed at one end to a stationary bracket and pivotally connected at its center with an extension on the armature of a selective electromagnet, a series of operating-electromagnets controlled by said circuit-closers, and a series of recording devices actuated by the operating-electromagnets and adapted to record signals at a distant station, substantially as set forth.

7. An electrical signaling system having means for sending to the main line signal impulses having a graded electromotive force combined with a main line, a main-line battery, a series of selective electromagnets the

windings of which are arranged in parallel and have a graded electromotive force, a series of interdepending circuit-closers actuated by said selective electromagnets, one contact-finger of each local-circuit closer being controlled by one selective electromagnet and the companion contact-finger by the next adjacent selective electromagnet, a series of operating-electromagnets controlled by said circuit-closers, and a series of recording devices actuated by the operating-electromagnets and adapted to record signals at a distant station, substantially as set forth.

8. An electrical signaling system having means for sending to the main line signal impulses having a graded electromotive force combined with a main line, a main-line battery, a series of selective electromagnets the windings of which are arranged in parallel and have a graded electromotive force, a series of interdepending circuit-closers actuated by said selective electromagnets, one contact-finger of each local-circuit closer being controlled by one selective electromagnet and the companion contact-finger by the next adjacent selective electromagnet and the final contact-finger of a series by a fixed support on the main frame, a series of operating-electromagnets controlled by said circuit-closers, and a series of recording devices actuated by the operating-electromagnets and adapted to record signals at a distant station, substantially as set forth.

9. An electrical signaling system having means for sending to the main line signal impulses having a graded electromotive force combined with a main line, a main-line battery, a series of selective electromagnets the windings of which are arranged in parallel and have a graded electromotive force, a series of interdepending circuit-closers actuated by said selective electromagnets, one contact-finger of each local-circuit closer being controlled by one selective electromagnet and the companion contact-finger by the next adjacent selective electromagnet the said companion finger comprising a bar or member fulcrumed at one end to a stationary bracket and pivotally connected at its center with an extension on the armature of a selective electromagnet, a series of operating-electromagnets controlled by said circuit-closers, and a series of recording devices actuated by the operating-electromagnets and adapted to record signals at a distance, substantially as set forth.

10. An electrical signaling system having means for sending to the main line signal impulses having a graded electromotive force combined with a main line, a main-line battery, a series of selective electromagnets the windings of which are arranged in parallel and have a graded electromotive force, a series of interdepending circuit-closers actuated by said selective electromagnets, one contact-finger of each local-circuit closer being controlled by one selective electromagnet

and the companion contact-finger by the next adjacent selective electromagnet and the final contact-finger of the series by a fixed support on the main frame, the said companion finger comprising a bar or member fulcrumed at one end to a stationary bracket and pivotally connected at its center with an extension on the armature of a selective electromagnet, series of operating-electromagnets controlled by said circuit-closers, and a series of recording devices actuated by the operating-electromagnets and adapted to record signals at a distant station, substantially as set forth.

11. In a printing-telegraph system, the combination of counterpart combined sending and receiving instruments at the respective stations, a main line, a main-line battery, each instrument being provided with an electrical resistance divided into sections that are connected in series, individual branch wires between the main-line battery and the resistance-sections, a series of sending-keys controlling the branch circuits and adapted to send to the main line signals of a graded electromotive force, a series of selective electromagnets having windings of a graded electromotive force, a series of interdepending circuit-closers actuated by said selective magnets, a series of local-battery circuits controlled by said circuit-closers, a series of electromagnets in said local circuits and a series of type-bars operated by said electromagnets, substantially as set forth.

12. In a printing-telegraph system, the combination of counterpart combined sending and receiving instruments at the respective stations, a main line, a main-line battery, each instrument being provided with an electrical resistance divided into sections that are connected in series, individual branch wires between the main-line battery and the resistance-sections, a series of sending-keys controlling the branch circuits and adapted to send to the main line signals of a graded electromotive force, a series of selective electromagnets the windings of which are arranged in parallel and have a graded electromotive force, a series of interdepending circuit-closers actuated by said selective magnets, a series of local-battery circuits controlled by said circuit-closers, a series of electromagnets in said local circuits and a series of type-bars operated by said electromagnets, substantially as set forth.

13. In a printing-telegraph system, the combination of counterpart combined sending and receiving instruments at the respective stations, a main line, a main-line battery, each instrument being provided with an electrical resistance divided into sections that are connected in series, individual branch wires between the main-line battery and the resistance-sections a series of sending-keys controlling the branch circuits and adapted to send to the main line signals of a graded electromotive force, a series of selective electro-

magnets the windings of which are arranged in parallel and have a graded electromotive force, a series of interdepending circuit-closers actuated by said selective magnets, one contact-finger of each local-circuit closer being controlled by one selective electromagnet and the companion contact-finger by the next adjacent selective electromagnet, a series of local-battery circuits controlled by said circuit-closers, a series of electromagnets in said local circuits, and a series of type-bars operated by said electromagnets, substantially as set forth.

14. In a printing-telegraph system, the combination of counterpart combined sending and receiving instruments at the respective stations, a main line, a main-line battery, each instrument being provided with an electrical resistance divided into sections that are connected in series, individual branch wires between the main-line battery and the resistance-sections, a series of sending-keys controlling the branch circuits and adapted to send to the main line signals of a graded electromotive force, a series of selective electromagnets the windings of which are arranged in parallel and have a graded electromotive force, a series of interdepending circuit-closers actuated by said selective magnets, one contact-finger of each local-circuit closer being controlled by one selective electromagnet and the companion contact-finger by the next adjacent selective electromagnet and the final contact-finger of the series by a fixed support on the main frame, a series of local-battery circuits controlled by said circuit-closers, a series of electromagnets in said local circuits, and a series of type-bars operated by said electromagnets, substantially as set forth.

15. In a printing-telegraph system, the combination of counterpart combined sending and receiving instruments at the respective stations, a main line, a main-line battery, each instrument being provided with an electrical resistance divided into sections that are connected in series, individual branch wires between the main-line battery and the resistance-sections, a series of sending-keys controlling the branch circuits and adapted to send to the main line signals of a graded electromotive force, a series of selective electromagnets the windings of which are arranged in parallel and have a graded electromotive

force, a series of interdepending circuit-closers actuated by said selective magnets, one contact-finger of each local-circuit closer being controlled by one selective electromagnet and the companion contact-finger by the next adjacent selective electromagnet, the said companion finger comprising a bar or member fulcrumed at one end to a stationary bracket and pivotally connected at its center with an extension on the armature of a selective electromagnet, a series of local-battery circuits controlled by said circuit-closers, a series of electromagnets in said local circuits, and a series of type-bars operated by said electromagnets, substantially as set forth.

16. In a printing-telegraph system, the combination of counterpart combined sending and receiving instruments at the respective stations, a main line, a main-line battery, each instrument being provided with an electrical resistance divided into sections that are connected in series, individual branch wires between the main-line battery and the resistance-sections, a series of sending-keys controlling the branch circuits and adapted to send to the main line signals of a graded electromotive force, a series of selective electromagnets the windings of which are arranged in parallel and have a graded electromotive force, a series of interdepending circuit-closers actuated by said selective magnets, one contact-finger of each local-circuit closer being controlled by one selective electromagnet and the companion contact-finger by the next adjacent selective electromagnet and the final contact-finger of the series by a fixed support on the main frame, the said companion finger comprising a bar or member fulcrumed at one end to a stationary bracket and pivotally connected at its center with an extension on the armature of a selective electromagnet, a series of local-battery circuits controlled by said circuit-closers, a series of electromagnets in said local circuits, and a series of type-bars operated by said electromagnets, substantially as set forth.

Signed at Chicago, Illinois, this 12th day of March, 1901.
